TRIGGER SAFETY ATTACHMENT FOR
FIREARMSBen B. Baker and Harold J. Gates,
Lone Pine, Calif.

Application June 14, 1948, Serial No. 32,753

4 Claims. (Cl. 42—70)

1

This invention is concerned with an attachment for firearms and it is a general object of the invention to provide a simple, practical, effective structure applicable to firearms to form a safety control in connection with the trigger or triggers thereof.

Firearms such, for example, as rifles or guns are usually provided with bolts, catches, or latches in connection with the hammers and designed to prevent accidental operation. The usual safety bolt or latch of the character referred to is such as to require deliberate operation and is not always as convenient and quick to operate as the user would prefer.

It is a general object of this invention to provide a structure applicable to a gun preferably as an attachment and operating to control the trigger or triggers thereof so that the gun cannot be fired until the attachment has been actuated.

It is a general object of this invention to provide an attachment of the general character referred to which is particularly suitable for and practical in connection with guns involving more than one trigger. The invention can be used to advantage in connection with a double barreled shotgun or the like wherein there are two triggers, one arranged forward of the other.

A further object of this invention is to provide a trigger control of the general character referred to applicable to a gun without material alteration or reconstruction thereof and in such manner as to in no way encumber or complicate the gun construction or action.

A further object of this invention is to provide a trigger control of the general character referred to in which the element engaging the trigger or triggers to control the action thereof is a simple reciprocating plate operating adjacent the stock where the triggers are located so that the finger portions of the triggers are entirely free and unobstructed.

The various objects and features of our invention will be fully understood from the following detailed description of a typical preferred form and application of the invention, throughout which description reference is made to the accompanying drawings, in which:

Fig. 1 is a side elevation of a typical double-barreled gun, say for example a shotgun, having two triggers, certain portions of the structure being broken away to show in section, the safety device being shown set or engaged. Fig. 2 is an enlarged side elevation of a portion of the structure shown in Fig. 1 showing in detail the manner in which the structure of the present inven-

2

tion is combined with the triggers of the gun and showing the safety device actuated or released. Fig. 3 is an enlarged detailed sectional view taken as indicated by line 3—3 on Fig. 2, and Fig. 4 is an enlarged detailed sectional view taken as indicated by line 4—4 on Fig. 2.

The structure provided by the present invention may be advantageously employed as an attachment in that it can be readily embodied in a form applicable to an ordinary or conventional gun such as a shotgun or the like without material alteration or modification thereof. In the following description reference will be had to a form of the invention intended as an attachment applicable to a conventional shotgun. However, it is to be understood that if desired the invention may be incorporated in a structure permanently built into or incorporated in a gun in the course of manufacture.

The structure of the present invention is applicable, generally, to guns such as rifles or shotguns. However, it is particularly practical as applied to a double-barreled gun such as a double-barreled shotgun wherein there are two triggers controlling the fire of the two barrels, the triggers being arranged in tandem. In this application the bulky elements of the structure embodying the present invention are arranged adjacent and immediately rearward of the rearmost trigger and consequently do not in any way interfere with or complicate the triggers.

In the drawings the invention is shown applied to a typical double-barreled shotgun including a stock A, hammers B carried by the stock on a hammer pin 10, sears C controlling the hammers and carried on a sear pin 11, triggers D and E controlling the hammers B through the sears C, and various other elements common to gun construction of this general character, such, for example, as main springs 12 operating the hammers, sear springs 13 operating the sears, etc. In accordance with conventional gun construction a trigger guard F is carried by the stock A at its lower side and is a loop-shaped element surrounding the triggers and intended to protect them against accidental operation. In practice the guard F is secured to the stock A of the gun and for all intents and purposes is a fixed or rigid part of the gun structure permanently shielding or guarding the two triggers D and E. The triggers D and E are arranged in tandem, that is, one behind the other, the trigger D being foremost, and in accordance with conventional gun construction it is cooperatively related with the sear C controlling the hammer for the right bar-

rel of the gun. The trigger E is located far enough behind the trigger D to enable the user to insert a finger between the triggers and it controls the sear which governs action of the hammer B for the left barrel of the gun. In accordance with conventional gun construction the triggers are carried on a trigger pin 15 and each includes a finger piece 16 curved to comfortably receive the finger of the operator and in the case shown each trigger has a web-like extension 17 projecting upwardly from the upper rear portion of the finger piece which extension cooperates with the sear in the manner common to firearms of this character.

The structure provided by the present invention is in the nature of a reciprocating control acting to simultaneously control both triggers and in its preferred form it is characterized by a reciprocating control plate G which contacts the triggers. The form of the invention illustrated in the drawings includes mounting means H for the control plate G, means J normally yieldingly holding the control plate in engagement with the triggers, and operating means K by which the plate may be conveniently operated or reciprocated out of engagement with the triggers.

The control plate G in its preferred form is slidable on the flat bottom side 20 of the stock A within the guard F and having portions immediately to the rear of the extensions or projections 17 of the triggers. The mounting means H provided by the present invention is such as to support the plate G so that it operates or reciprocates longitudinally of the gun and the plate is such that when it is in a forward position it has cooperative engagement with the triggers but is clear of the triggers when in the rear or retracted position. In the case illustrated, which is typical of double barreled shotguns the extensions or projections 17 of the triggers where they enter the stock are at different points lengthwise of the gun. To accommodate the situation or relationship of parts just referred to the plate G has trigger-engaging shoulders 21 and 22 located at different points lengthwise of the plate, the shoulder 21 being forward of shoulder 22 and such as to engage the projecting part 17 of the forward trigger D while the shoulder 22 is located to cooperate with or engage the part 17 of trigger E. It is preferred to relate the shoulders 21 and 22 to the parts 17 of the two triggers so that the shoulders simultaneously engage the triggers when the plate is moved forward and simultaneously release the triggers when the plate is moved rearward.

The present invention contemplates engagement of the triggers by the plate G so that when the plate is in the forward position shown in Fig. 1 the triggers are locked against operation. In the particular form of the invention illustrated the extension or projection 17 of each trigger is provided with a rearwardly opening notch or recess 25 and the shouldered portions of the plate engage in the recesses when the plate is in the forward position.

The means H mounting the plate on the gun preferably mounts the plate directly on the stock A of the gun, for instance, on the flat underside 20 of the stock within the guard, as shown in the drawings. In the particular form of the invention illustrated the means H involves a simple mounting screw having a threaded portion 30 engaged in the stock of the gun, a shank portion 31 extending through an elongate slot or

opening 33 in the plate G, and a head 34 retaining the plate in position on the shank portion 31.

The means K provided for operating the plate G acts to slide or shift the plate rearwardly from a forward engaged position such as is shown in Fig. 1, to a rear released position such as is shown in Figs. 2 and 3. In the particular form of the invention illustrated the operating means K involves a lever and the lever is preferably a simple bell crank having arms 40 and 41 joined at a fulcrum point 42. The arm 40 is a short arm arranged adjacent the rear end portion of the guard F while the arm 40 is a long arm extending rearwardly from the guard beneath the stock A to the rear of the guard. The fulcrum portion of the lever is shown merely bearing upon the guard providing a pivotal engagement between the lever and the guard. The operating means further includes a link connecting the short arm 40 of the lever and the plate G. The link is shown in the form of a simple rod 43 slidably passing through an opening 44 in the rear end portion of the guard and having its forward end engaged with an ear 45 on the plate while its rear end is coupled to the arm 40. The ear 45 is shown formed on or projecting from the rear end of plate G and the rear end portion of the rod is shown fitted freely through an opening 46 in the arm 40. The rod is coupled to the ear 45 by a head 47 on the forward end of the rod and is provided at its rear end with a head 48 that engages the arm 40 as clearly shown in Fig. 2 of the drawings. With the construction just described depression of the long arm 41 in the direction indicated by the arrow in Fig. 1 causes the lever to pivot about the fulcrum point 42 so that the arm 40 swings rearwardly carrying the link or rod 43 with it. As the link 43 moves rearwardly the plate G is moved rearwardly and out of engagement with the triggers.

The means J serves to normally yieldingly hold the plate G in a forward position where the shouldered portions of the plate are engaged in the notches of the triggers. In the form of the invention illustrated the means J involves a simple helical spring 50 carried on the rod 43 between the rear end portion of the guard F where the opening 44 is located and the ear 45 on the plate G. Spring 50 is a compression spring acting under compression between the ear 45 and the guard F so that it normally yieldingly urges the plate forward. The link or rod 43 serves as an effective guide and support for the spring maintaining the spring in proper operating position between the guard and the plate.

From the foregoing description it will be apparent that the structure provided by the present invention can be applied to a typical or conventional gun by merely notching the triggers to form the notches 25 and forming a passage or opening 44 through the guard to pass the rod 43. The structure involves few simple yet dependable parts and under normal conditions the plate G is urged forward to latch or engage in the notches in the triggers and normally hold the triggers against operation. Before the gun can be fired the user or operator must depress the long arm 41 of the control lever in the direction indicated by the arrow in Fig. 1, and when the lever is thus depressed the guard-plate is shifted so that both triggers are simultaneously released, making the gun ready for use.

Having described only a typical preferred form and application of our invention, we do not wish

to be limited or restricted to the specific details herein set forth, but wish to reserve to ourselves any variations or modifications that may appear to those skilled in the art and fall within the scope of the following claims.

Having described our invention, we claim:

1. An attachment for a gun having a stock carrying a trigger and a trigger guard including, a plate, means mounting the plate on the stock to shift relative to the trigger, means normally yieldingly holding the plate in engagement with the trigger holding the trigger against operation, and an operator for the plate shifting the plate away from the trigger including a lever pivoted on the guard and projecting rearward from the guard and a link between the lever and plate and guided by the guard, the first mentioned means including a compression spring on the link between the plate and guard.

2. An attachment for a gun having a stock, triggers carried by the stock and a guard over the triggers, a plate, means mounting the plate on the stock entirely within the guard to shift into engagement with the triggers, a spring normally yieldingly holding the plate in holding engagement with the triggers, a lever at the rear of the guard wholly supported by the guard to pivot relative thereto, and an operating link from the lever to the plate, the spring being a compression spring carried on the link within the guard and between the plate and the guard.

3. An attachment for a gun having a stock carrying a trigger and an apertured trigger guard including, a plate, means mounting the plate on the stock entirely within the guard to shift relative to the trigger, means entirely within the confines of the guard normally yieldingly holding

the plate in engagement with the trigger and stopping the trigger against operation, and an operator for the plate shifting the plate away from the trigger including, a lever bearing on the exterior of the guard and having a finger portion projecting rearward from the guard, and a substantially straight elongate link carrying the lever and connecting the lever and plate, the link being slidably carried in the aperture of the guard.

10 4. An attachment for a gun having a stock, triggers carried by the stock and an apertured guard having spaced ends mounted on the stock extending over the triggers including, a plate with a projection thereon, a single screw slidably 15 mounting the plate on the exterior of the stock between the ends of the guard and entirely within the confines of the guard to shift into engagement with the triggers, a spring within the guard and between said projection on the plate and one 20 end of the guard normally yieldingly holding the plate in holding engagement with the triggers, an L-shaped lever at the rear of the guard supported to pivot relative thereto, and a substantially straight elongate operating link extending from 25 the lever to the plate and slidably extending through the aperture of the guard.
